(57) **CLAIM**

The ornamental design for a wireless controller, as shown and described.

DESCRIPTION

FIG. 1 is a front-bottom-right perspective view of a wireless controller showing my new design;

FIG. 2 is a rear-top-right perspective view thereof;

FIG. 3 is a front elevational view thereof;

FIG. 4 is a rear elevational view thereof;

FIG. 5 is a top plan view thereof;

FIG. 6 is a bottom view thereof; and,

FIG. 7 is a right-side elevational view thereof, the left-side elevational view being a mirror image thereof.

The broken lines showing portions of the wireless controller form no part of the claimed design.

1 Claim, 7 Drawing Sheets
